CLAIM

The ornamental design for an automatic cleaning robot for swimming pool, as shown and described.

DESCRIPTION

Fig. 1.1 is a bottom plan view of an automatic cleaning robot for swimming pool, showing my new design;

Fig. 1.2 is a rear elevation view thereof;

Fig. 1.3 is a top plan view thereof;

Fig. 1.4 is a left side elevation view thereof;

Fig. 1.5 is a top, rear, and right side perspective view thereof;

Fig. 1.6 is a right side elevation view thereof; and

Fig. 1.7 is a front elevation view thereof.
